UNITED STATES PATENT OFFICE.

MELVIN L. STONE, OF PROVIDENCE, RHODE ISLAND, ASSIGNOR TO DRAPER CORPORATION, OF HOPEDALE, MASSACHUSETTS, A CORPORATION OF MAINE.

INTERMITTENT THREAD-CUTTING TEMPLE FOR LOOMS.

Application filed June 1, 1926. Serial No. 112,749.

This invention relates to improvements in an intermittently operated thread cutting temple for looms.

The object of the invention is to provide a simple and efficient construction in which the thread cutting elements shall be operated at the time of replenishment only for a predetermined period, thus saving wear and tear during the remaining operation of the loom.

Various mechanisms have heretofore been provided for securing the intermittent operation of the thread cutting temple because the continued operation of the cutting elements after the severance of the filling upon replenishment and until the time of the next replenishment is entirely unnecessary and wasteful. The present invention is designed to effect this result by means readily applied to existing constructions and by mechanism which is of simple construction and capable of functioning efficiently, notwithstanding the shock and jar to which it is subjected.

The object of the invention is further to provide such a mechanism which may be timed to secure any desired number of cutting movements after replenishment has taken place in accordance with the character of the work being performed and the conditions of the operation of the loom.

These and other objects and features of the invention will appear more fully from the accompanying description and drawings and will be particularly pointed out in the claims.

As the invention is concerned solely with the means for securing the operation of the cutting instrumentalities only at and during predetermined periods and is applicable to various forms of thread cutting temples and will be readily understood by those skilled in the art, it is only necessary here to illustrate and describe certain portions of the loom and an ordinary type of thread cutting temple sufficient to disclose a preferred embodiment of the invention.

In the drawings:

Fig. 1 is a view in side elevation of a portion of a loom, a thread cutting temple and a mechanism embodying the invention with the thread cutter shown in inoperative position.

Fig. 2 is a view similar to Fig. 1 with the thread cutter shown in operative position.

Fig. 3 is a detail partially broken away

in front elevation of a portion of the mechanism shown in Fig. 1.

A portion of the frame 1 of the loom, the lay 2, the controller shaft 3, and the temple-supporting bracket 4 are shown of a usual and familiar construction.

The temple, as already pointed out, may be of any suitable form and construction and for convenience is herein illustrated as of the type shown in the patent to Stimpson, No. 1,366,034, January 18, 1921. Such a device comprises a temple stand 5 mounted on the bracket 4 and a temple having a head 6 at the rearward end of a shank 7 which is mounted for rearward and forward movement in the stand.

The forward movement is given by the engagement of the lay 2, upon the beat up, with the downwardly projecting heel 8 of the temple and the rearward movement by the usual spring 9 surrounding the temple shank within the stand 5. The cutting instrumentalities comprise a fixed cutter blade, not shown, in the temple head and a movable cutter member 10 mounted in a slot in the temple head to have a forward and rearward rocking movement of the usual character. This movable cutter member at its rearward end is provided with a hook-shaped blade 11 cooperating with the fixed blade to sever the filling when the cutter member is moved forwardly and downwardly.

The movements of the movable cutter member are given in the usual manner. A spring 12 connected at its upper end to the temple shank and at its lower end to a stud 13 on the depending heel 14 of the movable cutter member acts to give the rearward movement, while the lay 2 on the beat up engaging the heel 14 acts to give the forward movement. Consequently under usual conditions the movable cutter member is moved forwardly by the lay at each beat-up and then immediately projected rearwardly by the spring 12, thus being in constant operation while the loom is running. But this movement of the movable cutter member is required only when, and immediately after, replenishment has taken place for the purpose of severing the filling ends left as a result of the replenishing operation. One or at most but a few of the operations of the thread cutter are required for this purpose and the present invention is for the purpose of limiting the operation of the

movable thread cutter member so that its operation shall only take place when thus required and for limited, predetermined periods.

5 In the preferred construction illustrated a ratchet wheel 15 is rotatably mounted on the temple. As a convenient means for thus mounting the ratchet wheel, a bracket 16 is secured by means of a set screw 17 to the temple shank 7 and depends therefrom. At 10 its lower end it is provided with a hub 18 carrying a stud 19 on which is rotatably mounted the ratchet wheel 15.

A retractor in the form of a link 20 is 15 connected to the movable cutter member and is engaged and moved by the ratchet wheel when rotated to draw the movable cutter member forward to inoperative position. This retractor has its connection with the 20 movable cutter member by being pivoted, in the form shown, on the stud 13 at its rear end and engages the ratchet wheel by means of a slot 21 at its forward end fitting over a pin 22 extending laterally from the ratchet 25 wheel.

The ratchet wheel is actuated to carry the pin 22 around counter-clockwise and thus to draw the movable cutter member forwardly to inoperative position by means of 30 an actuating pawl carried and moved by the movable cutter member itself. This pawl 23 for that purpose is conveniently carried by the movable cutter member by being pivoted at 24 to the retractor 20 which in turn 35 is carried by the movable cutter member. It will thus be seen that when the movable cutter member is free to operate, it will be moved forward at each beat-up of the lay causing the pawl 23 to engage the ratchet 40 wheel 15 and move the ratchet wheel one or more teeth at a time until the pin 22 has carried the retractor forward, and with it the movable cutter member, to a position where the lay can no longer strike and move 45 the heel 14. Reverse rotation of the ratchet wheel is prevented by a suitable detent pawl 25 engaging the ratchet wheel and herein shown as pivoted at 26 on the bracket 16 carried by the temple shank 7.

50 When the pawls are not in engagement with the ratchet wheel, the spring 12 acts to restore the movable cutter member to its rearward operative position and in addition a spring 27 may be employed to assist in the 55 reverse rotation of the ratchet wheel. This spring is mounted on the hub 18 of the bracket 16 and engages at one end the bracket and at the other end the ratchet wheel.

The engagement and disengagement of the 60 pawls with the ratchet wheel is controlled by a pawl lifter. In the construction illustrated, this pawl lifter is shown as a bar 28 having at its rearward end an arm 29 extending beneath pins 30 and 31 projecting laterally from the pawls 23 and 25, respec-

tively. The pawl lifter is so mounted, in the construction illustrated, as to have both a forward and rearward movement and a vertical up and down movement. For this purpose the bar 28 slides in brackets 32 on the temple stand and is provided with suitable cam surfaces 33 cooperating with said brackets. The rearward movement of the pawl lifter is limited by a pin 34 engaging the left-hand bracket and the forward movement by the vertical portion 35 engaging the right-hand bracket.

The movement of the pawl lifter to free the pawls 23 and 25 from the ratchet wheel and allow the movable cutter member to move to operative position is preferably secured upon the call for filling replenishment from the usual controller shaft 3. This shaft rocks counter-clockwise when replenishment is called for and, in the construction illustrated, an arm 36 is mounted on this shaft and a spring 37 connects the upper end of the arm 36 to the end of the pawl lifter 28 so that when replenishment is called for and the arm 36 swings to the left, the pawl lifter is drawn forwardly until the vertical portion 35 engages the right-hand bracket 32 and then any further movement of the arm 36 is taken up by the spring 37. The controller shaft 3 after its actuating movement immediately rocks in the opposite direction and thereupon the pawl lifter, in the construction illustrated, moves to permit restoration of the pawls to engagement with the ratchet wheel under the influence of a spring 38, shown as connected at one end to the bracket 32 and at the other end to a pin 39 on the pawl lifter.

An important feature of the pawl lifter construction resides in the construction by which it permits the bodily forward and rearward movement of the pawls when the pawl lifter is in either position without interfering with the proper functioning of the pawls. In Fig. 1 the pawls are shown in engagement with the ratchet wheel. If now the entire temple is carried forwardly by the lay, the pawl studs 30 and 31 ride along or above the surface 40 of the pawl lifter and still remain in engagement with the ratchet wheel. The stud 30 of the actuating pawl also rides along or above this surface while the pawl lifter is in this position and the ratchet wheel is being operated to retract the movable cutter member to its inoperative position. So also, as shown in Fig. 2, when the pawl lifter is in elevated position and the movable cutter member is functioning, if bodily forward movement of the entire temple takes place, the studs 30 and 31 ride along on the surface 40 while held disengaged from the ratchet wheel.

The number of operations of the movable cutter member which takes place after it has moved into operative position is deter-

mined, first, by the extent to which the ratchet wheel is moved by the pawl 23 upon each forward movement of the movable cutter member and, second, upon the extent to which reverse rotation of the ratchet wheel takes place when the pawls are disengaged by the pawl lifter. This extent of reverse rotation is adjusted, in this invention, by means of cooperating relatively adjustable stops on the temple and ratchet wheel. In the construction illustrated, one of these stops is shown as a pin 42 secured in the ratchet wheel and extending laterally thereof and the other as a pin 43 which is set as required in one or the other of holes 44 in the hub 18. It is thus possible to control the number of movements of the movable cutter member to any number required to effect the severance of the filling under the particular conditions.

The operation of the mechanism illustrated will be apparent from the description already given. Normally the parts stand as shown in Fig. 1 with the movable cutter member in its retracted forward inoperative position. When now the call for filling replenishment occurs and the controller rock shaft 3 rocks, the pawl lifter 28 is drawn to the left and by the cam surfaces 33 is raised, thus lifting both the actuating pawl 23 and the detent pawl 25 from engagement with the ratchet wheel, as shown in Fig. 2, and immediately, under the actuation of the springs 12 and 27, the movable cutter member moves rearwardly to its operative position and the ratchet wheel rotates clockwise until the pin 42 engages the pin 43. As the lay now beats up, it engages the heel 14 of the movable cutter member and operates it to give the cutting movement in the usual manner. But immediately the controller rock shaft 3 rotates in the opposite direction and the spring 38 moves the pawl lifter 28 to the right and the cam surfaces 33 force it downwardly, thus permitting the pawls 23 and 25 to be restored to cooperative engagement with the ratchet wheel. The next forward movement of the movable cutter member that takes place causes the actuating pawl 23 to rotate the ratchet wheel and move the pin 22. The extent to which this pin moves is determined by the extent to which the pawl 23 moves the ratchet wheel and the rotary position of the pin 22 as determined by the stops 42 and 43. In any event, after one or more operations of the movable cutter member, the pin 22 will engage the end of the slot 21 in the retractor 20 and move the movable cutter member to its forward inoperative position.

It will thus be seen that the invention provides a simple and efficient type of mechanism which may readily be embodied in existing loom structures as well as in new

structures, and which insures the operation of the thread cutting mechanism only at and during predetermined periods and preferably only at the time of replenishment as required for severing the filling ends left when replenishment takes place.

Having thus described the invention, what is claimed as new, and desired to be secured by Letters Patent, is:

1. An intermittent thread cutting temple for looms comprising a movable cutter member receiving its forward cutting movement from the lay, a spring acting to move the cutter member rearwardly, a ratchet wheel mounted on the temple, an actuating pawl carried and moved by the movable cutter member for rotating the ratchet wheel, a retractor connected to the movable cutter member and engaging and moved by the ratchet wheel when rotated by the actuating pawl to draw the movable cutter member forward to inoperative position, a detent pawl to hold the ratchet wheel against reverse rotation, a pawl lifter cooperating with the actuating and detent pawls, and means for actuating the pawl lifter upon the call for filling replenishment to lift the pawls from engagement with the ratchet wheel and permit the movable cutter member to assume its rearward operative position.

2. An intermittent thread cutting temple for looms comprising a movable cutter member receiving its forward cutting movement from the lay, a spring acting to move the cutter member rearwardly, a ratchet wheel mounted on the temple, an actuating pawl carried and moved by the movable cutter member for rotating the ratchet wheel, a retractor connected to the movable cutter member and engaging and moved by the ratchet wheel when rotated by the actuating pawl to draw the movable cutter member forward to inoperative position, a detent pawl to hold the ratchet wheel against reverse rotation, a pawl lifter cooperating with the actuating and detent pawls, and means for momentarily actuating the pawl lifter at the time of replenishment to lift the pawls from engagement with the ratchet wheel and permit the movable cutter member to assume its rearward operative position and then to permit the restoration of the pawls to cooperative engagement with the ratchet wheel.

3. An intermittent thread cutting temple for looms comprising the construction defined in claim 1, in which the retractor is pivotally connected to the movable cutter member and in which the actuating pawl is pivotally mounted on the retractor.

4. An intermittent thread cutting temple for looms comprising the construction defined in claim 1, in which the ratchet wheel is provided with a laterally projecting pin, the retractor is pivotally connected to the

movable cutter member and provided with a slot engaging said pin and in which the actuating pawl is pivotally mounted on the actuator.

5. An intermittent thread cutting temple for looms comprising the construction defined in claim 2, together with cooperating relatively adjustable stops on the temple and ratchet wheel to limit the reverse rotation of the ratchet wheel and consequently the number of movements of the movable cutter member before it is drawn forward to inoperative position.

6. An intermittent thread cutting temple for looms comprising a temple stand, a temple bodily movable in said stand, a movable cutter member receiving its forward cutting movement from the lay, a spring acting to move the cutter member rearwardly, a ratchet wheel mounted on the temple, an actuating pawl carried and moved by the movable cutter member for rotating the ratchet wheel, a retractor connected to the movable cutter member and engaging and moved by the ratchet wheel when rotated by the actuating pawl to draw the movable cutter member forward to inoperative position, a detent pawl on the temple to hold the ratchet wheel against reverse rotation, a pawl lifter hav-

ing an arm extending beneath the actuating and detent pawls and mounted for longitudinal and vertical movement on the temple stand, means for giving a forward and upward movement to the pawl lifter followed by a rearward and downward movement at the time of replenishment, thus first to lift the pawls from engagement with the ratchet wheel and then to permit their restoration to engagement with the ratchet wheel.

7. An intermittent thread cutting temple for looms comprising the construction defined in claim 6, in which the arm of the pawl lifter is shaped to permit bodily forward and rearward movement of the pawls with the temple without interfering with the required functioning of the pawls when the pawl lifter is in either position.

8. An intermittent thread cutting temple for looms comprising the construction defined in claim 6 in which the pawl lifter is given its forward and upward movement upon the call for filling replenishment and its downward and rearward movement by a spring connecting the pawl lifter to the temple stand.

In testimony whereof, I have signed my name to this specification.

MELVIN L. STONE.
